UNITED STATES PATENT OFFICE.

CHARLES J. SYKES, OF CHICAGO, ILLINOIS, ASSIGNOR TO LEWIS J. BRAINARD, OF CHICAGO, ILLINOIS.

DIE-CASTING MACHINE.

Application filed September 2, 1927. Serial No. 217,140.

It is necessary in die casting machines that the sections of the die or mold be held together with considerable pressure; and the object of the present invention is to produce a simple and novel mechanism for moving one half of the die from and toward the other half and firmly pressing it against the latter preparatory to the injection of the metal into the die.

10 The various features of novelty whereby my invention is characterized will herein-after be pointed out with particularity in the claims; but, for a full understanding of my invention and of its objects and advantages, 15 reference may be had to the following detailed description taken in connection with the accompanying drawings, wherein:

Figure 1 is a side elevation of the machine embodying the present invention; Fig. 2 is 20 an elevation on an enlarged scale, showing the operating mechanism for the movable die element; Fig. 3 is a view similar to Fig. 2, showing different positions of the parts, one half of the double cam being omitted in each 25 of Figs. 2 and 3; Fig. 4 is a view looking toward Fig. 2 from the left hand side, both cam members being shown; Figs. 5, 6 and 7 are sections on an enlarged scale, taken respectively on lines 5-5, 6-6, and 7-7, of 30 Fig. 2.

Referring to the drawings, 1 represents the horizontal upper portion of the frame of a die casting machine. Mounted on the frame is a die divided into two halves 2 and 35 3, along a transverse vertical plane; the member 2 being stationary and the member 3 being slidable along the frame from and toward the member 2. In the arrangement shown, the movable die member is carried by a long 40 slide 4 suitably guided by the frame.

The machine is provided with a suitable transverse cam shaft 5 below the upper part of the frame and beyond the left hand end of the slide. A long bolt-like rod 6 is rigidly 45 supported from the frame at a suitable distance above the die, the rod extending lengthwise of the machine. In the arrangement shown, the bar is supported at its ends in pedestals, 7 and 8 rising respectively from the left hand end of the machine and from the frame on the right hand side of the die. Fixed to the shaft 5 are two cam disks 9 and 50 10 each of which has a cam groove 11 on its inner side. Two vertical bars 12 extend upwardly from a point between the two cam

disks past the rod 6, lying on opposite sides of the rod. There is on rod 6 a block 14 having pins or projections 15 on the opposite sides. These pins or projections extend through elongated slots 16 in the upper ends 60 of the bars 12. On the lower end of each of the bars 12 is a cam roller 17 engaged with one of the continuous cam grooves. Therefore, as the shaft 5 revolves, the bars are moved up and down, being guided at their 65 upper ends by pin and slot connections with the rod 6. The lower ends of the bars are caused to move in an approximately vertical direction as the cams revolve, by means of a long arm 18 pivoted at one end to the lower 70 ends of the bars and at its other end to a remote point on the frame of the machine, as indicated at 19; the arm swinging through a small angle above and below a horizontal position as the bars rise and fall. As best 75 shown in Fig. 7, a single pin 20 may serve to connect together the members 12 and 18 and support the cam rollers 17.

The block 14 on rod 6 is provided with two ears 21 spaced apart from each other. The upper end of a cam plate 22 extends into the space between these ears and is pivotally connected to the ears by means of a transverse pin 23. The lower end of the cam plate is fastened to the slide 4 by means of a link 24. 80 The cam plate lies in the space between the bars 12. In the cam plate is a long slot within which lies a cam roller 25 arranged on a pin 26 extending through the same and through the two bars. The slot in the cam plate comprises two, straight sections arranged at an angle to each other, namely a long upper section 27 and a short lower section 28. The parts are so proportioned that when the bars are raised to their uppermost position by 85 cams 9 and 10, the cam roller 25 is in the upper end of the cam slot, causing the cam plate to be swung toward the left and thus holding the movable half of the die away from the stationary half. When the bars are drawn down from their uppermost position 90 illustrated in Fig. 3, the cam roller 25 being compelled to move in a vertical direction, the cam plate must swing toward the right, thus carrying the movable die member toward the stationary die member. Just before the bars reach their lowermost position the cam roller 25 enters the short section 28 forming the lower part of the cam slot. The 95 sides of this short section are now inclined 100

110

only they are slightly vertical, so that the swinging movement of the cam plate for a given downward movement of the bars is very small compared to the swinging movement of the cam plate for a corresponding downward travel of the bars while the cam roller is in section 27 of the slot. In other words, the travel of the movable die member is rapid as it approaches the stationary member, and, as it is about to contact with the stationary die member, its movement becomes very slow, but it is urged against the stationary die member under great pressure due to the powerful wedging action of the almost vertical lower end of the cam slot. Consequently the two halves of the die are pressed together with great force when the die is closed; while the major portions of the movements, in both directions, of the movable die member are rapid and thus permit the die to be quickly opened and closed.

While I have illustrated and described with particularity only a single preferred form of my invention, I do not desire to be limited to the exact structural details thus illustrated and described; but intend to cover all forms and arrangements which come within the definitions of my invention constituting the appended claims.

I claim:

1. In a machine of the character described, a die having a movable member, a reciprocatory device movable transversely with respect to the path of said member, an element connected to said member and having a slot inclined with respect to the path of said reciprocatory member, and an actuator carried by said device and extending into said slot, the slot being so shaped that movement of said element for a given length of travel of said device is very small when the actuator is near one end of the slot as compared with the movement of said element for a corresponding length of travel when the actuator is at other points in the slot.

2. In a machine of the character described, a die having a movable member, an element connected to said member and having a slot extending transversely with respect to the path of said member, and a reciprocatory device having an actuator extending into said

slot, the slot being so shaped and the direction of movement of said device being such that the extent of travel of such member for a given length of movement of said device is very small while said member is near die-closing position and is much greater at other points in the travel of said member.

3. In a machine of the character described, a die having a movable member, a swinging element having a slot extending transversely with respect to the path of said movable member, a connection between said element and said member, and a reciprocatory device having an actuator extending into said slot, said slot being so shaped that the swinging movement of said element for a given travel of the actuator is much less when the die is almost closed than at other times.

4. In a machine of the character described, a die having a movable member, a reciprocatory device movable transversely with respect to the path of said movable member, an element pivotally supported at one end and connected to said member at the other end, said element having a slot inclined with respect to the path of said device, the inclination of the slot being smaller at one end of the slot than at other points, and an actuator projecting from said device into said slot.

5. In a machine of the character described, a frame having a horizontal top portion, a die on the top of said frame and having a member movable along said horizontal top portion between a position in which the die is closed and a position in which the die is open, an element mounted at its upper end on the frame for swinging movements in a plane parallel with the path of the movement of said movable die member, a link connecting the lower end of said element with said movable die member, a device reciprocable in the vertical direction, said element having a slot inclined to the vertical, one end of the slot being inclined to a lesser degree than other portions of the slot, and an actuator carried by said device and projecting into said slot.

In testimony whereof, I sign this specification.

CHARLES J. SYKES.
